We claim the ornamental design for a power tool blade guard, as shown and described.

DESCRIPTION

FIG. 1 is a top perspective view of a power tool blade guard in accordance to our invention.

FIG. 2 is a left side view of the power tool blade guard of FIG. 1.

FIG. 3 is a right side view of the power tool blade guard of FIG. 1.

FIG. 4 is a front view of the power tool blade guard of FIG. 1.

FIG. 5 is a rear view of the power tool blade guard of FIG. 1.

FIG. 6 is a top view of the power tool blade guard of FIG. 1; and,

FIG. 7 is a bottom view of the power tool blade guard of FIG. 1.

The even broken lines in the drawings illustrate portions of the power tool blade guard that forms no part of the claimed design. The broken lines in dash-dot form illustrate boundaries of the claimed design and form no part of the claimed design.
